UNITED STATES PATENT OFFICE.

EDWIN A. MASTICK, JR., OF CLEVELAND, OHIO.

SHINGLE-STRIP.

1,298,535.

Specification of Letters Patent. Patented Mar. 25, 1919.

Application filed December 31, 1917. Serial No. 209,857.

To all whom it may concern:

Be it known that I, EDWIN A. MASTICK, Jr., a citizen of the United States, resident of Cleveland, county of Cuyahoga, and State 5 of Ohio, have invented new and useful Improvements in Shingle-Strips, of which the following is a specification, the principle of the invention being herein explained and the best mode in which I have contemplated applying that principle, so as to distinguish it 10 from other inventions.

My invention relates to shingles and particularly to gang shingles known to the trade as a shingle strip. Said invention is 15 designed to provide such strips which shall be economical in that they can be reversed, if injured, and in that material can be saved in cutting the same by the use of the cut ends; which shall be economical in their cost 20 of laying inasmuch as they are more easily handled because of their reversibility; and which shall be economical from the stand-point of long use because of the fact that 25 their construction does not allow them to vibrate or flap in the wind, but does allow the necessary compensation for the expansion and contraction of both the shingles and the roof members.

The annexed drawings and the following 30 description set forth in detail certain means embodying my invention, the disclosed means, however, constituting but one of various mechanical forms in which the principle of the invention may be employed.

35 In said annexed drawings:

Figure 1 represents a plan view of a section of roof covering comprised of my new and improved shingle strips; Fig. 2 represents a vertical longitudinal section taken 40 in the plane indicated by the line II—II, Fig. 1; Fig. 3 represents a plan view of a single strip; Fig. 4 represents a transverse vertical section taken in the plane indicated by the line IV—IV, Fig. 1; and Fig. 5 represents a longitudinal vertical section taken 45 in the plane indicated by the line V—V, Fig. 1.

Referring particularly to Fig. 3, it will be noted that a single strip comprises a body 50 member 1 formed with a plurality of spaced slots, the strip shown in Fig. 3, by way of illustration, comprising three sets of vertically aligned slots so as to form a gang shingle of four parts, said slots being three in number in each set and composed of comparatively long upper and lower slots 4 and 5, 55 respectively, and an intermediate smaller slot 6. It will be particularly pointed out that the said strip 1 is thus provided with continuous edges 2 and 3. These strips are 60 either standard 10" or standard 12 $\frac{1}{4}$ " in depth and, by way of illustrating the manner of laying the same, a number of strips of the 12 $\frac{1}{4}$ " depth are shown laid up to form a section of roof covering in Fig. 1, the exposure of each strip being 4". It is evident 65 that this will provide a narrow $\frac{1}{4}$ " section where the roofing 8 is four shingles in depth, and the slots 4, 5 and 6 are so disposed that the lower end of the slot 6 lies just immediately above this four shingle section and at this point the nails 7 are driven, as plainly shown in Figs. 1, 4 and 5. The heads of these nails are covered by the uppermost strip, as plainly shown in Figs. 4 and 5, and 70 said nails 7, in the illustration shown in the accompanying drawing, pierce one strip in addition to the strip containing the slot 6 through which they pass and then are driven into the roof parts 8 immediately above the 75 four thickness section, as hereinbefore mentioned. The slots 4, 5 and 6 are of such a width as to allow lateral movement of the shingle strip 1, as plainly shown at 80 Fig. 4. Of course, the slots 4, 5 and 6, as will be 85 readily understood, allow also for the longitudinal play of the nails when the roof boards 8 expand or contract and also allow for the expansion and contraction of the shingle strips themselves. The above-described disposition of the slots 4, 5 and 6 has 90 resulted in the formation of the comparatively narrow sections 9 and 12 of the shingle strip 1 disposed adjacently to the edges 95 2 and 3, respectively, as plainly shown in Fig. 3, and also in the sections 10 and 11 disposed intermediately of the slot 6 and the slots 4 and 5, respectively. The slots 4, 5 and 6 allow for the expansion and contraction 100 of the several shingles of the strip 1; whereas, the very narrow sections 9 and 12 will double or buckle without breaking during such contraction. By not running the slots 4 and 5 to the extreme edge of the shingle strip 1, I thereby provide the continuous 105 edges 2 and 3 which will not vibrate or flap in the wind to the great detriment of the shingles, as is well-known in the trade. I find it preferable in the laying of these shingle strips not to nail them extremely 110 tight. Whenever a double ply shingle is used, the end slots 4 and 5 are made longer

and the shingles are laid 5" to the weather. In laying up my improved shingle strip to form an improved roof covering, I so relatively dispose the several strips as to secure 5 a maximum staggering of the joints, parts of at least three different strips being disposed between adjacent joints, all as plainly seen in Fig. 1. Because of the better drainage and protection thus afforded, this method 10 of laying up the roof produces a much more efficient construction than any other of which I am aware and in which the joints are made by simply bi-secting the separate shingles.

From the above description and the accompanying drawing it is readily apparent 15 that my improved shingle strip is reversible so that it will save time in handling and will also save material by the ability to reverse and use if one edge is injured and also 20 will save material in cutting by reason of the use of the cut ends. By reason of the comparative movements of the roof boards, shingles and nails, allowed in the construction shown and described, the shingles will give 25 much longer service than any with which I am at present acquainted.

What I claim is:

1. A shingle strip consisting of a water- 30 proof felt formed with a plurality of sets of slots consisting each of three vertically aligned spaced slots, the respective upper and lower ends of the outer of which slots are removed somewhat from the top and bottom edges of the strip to form continuous 35 narrow marginal portions along said edges.

2. A shingle strip consisting of a water- 40 proof felt formed with a plurality of sets of slots consisting each of three vertically aligned spaced slots of which the upper and lower are great in length compared with the middle slot, the respective upper and lower ends of the outer of which slots are removed somewhat from the top and bottom edges of the strip to form continuous narrow 45 marginal portions along said edges.

3. A roof covering consisting of a plurality of shingle strips laid to overlap, each such strip formed in its body portion with three spaced vertically aligned slots; and 50 nails securing said strips together and the covering to the roof boards and disposed in the central slots of the several strips adjacently the lower ends of said slots.

4. A roof covering consisting of a plurality of shingle strips laid to overlap, each such strip formed in its body portion with three spaced vertically aligned slots; and nails securing said strips together and the covering to the roof boards and disposed in 60 the central slots of the several strips adjacently the lower ends of said slots and immediately above the top edges of the several lowermost strips.

5. A roof covering consisting of a plurality of shingle strips laid to so overlap that

parts of three or more strips are comprehended between joints; and means for securing said strips together and the covering to the roof boards.

6. A roof covering consisting of a plurality of shingle strips each formed with a plurality of sets of vertically aligned slots defining the several shingles, said strips being laid to so overlap that parts of three or more strips are comprehended between 75 joints; and means for securing said strips together and the covering to the roof boards.

7. A roof covering consisting of a plurality of shingle strips laid to overlap, each such strip formed in its body portion with a plurality of sets of vertically aligned slots, each such set consisting of comparatively large upper and lower slots and an intermediate small slot; and nails securing said strips together and the covering to the roof boards 80 and disposed in the lower ends of intermediate slots, the strips being so laid that the top edges of the lowermost strips are disposed adjacently below the nails, respectively. 85

8. A roof covering consisting of four shingle strips laid to overlap, each such strip formed in its body portion with a slot; and nails securing said strips together and the covering to the roof boards and disposed 90 in the several slots approximately midway the top and bottom edges of the strips in which said slots are formed, the strips being so laid that the lowermost strips are disposed adjacently below the nails, respectively, and 95 the uppermost strips cover the heads of said nails, whereby any one nail pierces only a single strip. 100

9. A roof covering consisting of four shingle strips laid to overlap, each such strip 105 formed in its body portion with vertically aligned spaced slots; and nails securing said strips together and the covering to the roof boards and disposed in slots of the several strips at points far removed from the top 110 and bottom edges of the strips in which said slots are respectively formed, the strips being laid so that the lowermost strips are disposed adjacently below the nails, respectively, and the uppermost strips cover the 115 heads of said nails, whereby any one nail pierces only a single strip. 120

10. A roof covering consisting of a plurality of shingle strips laid to overlap, each such strip formed in its body portion with vertically aligned spaced slots; and nails securing said strips together and the covering to the roof boards and disposed in slots of the several strips at points far removed from the top and bottom edges of the strips in which said slots are respectively formed, the strips being laid so that the lowermost strips are disposed adjacently below the nails, respectively, and the uppermost strips cover the heads of said nails. 125 130

11. A roof covering consisting of four shingle strips laid to overlap, each such strip formed in its body portion with vertically alined spaced slots defining the several shingles of the strip; and nails securing said strips together and the covering to the roof boards and disposed in slots of the several strips at points far removed from the top and bottom edges of the strips in which 5 said slots are respectively formed, the strips being so laid that the lowermost strips are disposed adjacently below the nails, respectively, and the uppermost strips cover the heads of said nails, whereby any single strip 10 is pierced only by nails one less in number than the number of shingles defined in said strip.
12. A roof covering consisting of four shingle strips laid to overlap, each such strip 20 formed in its body portion with vertically alined spaced slots defining the several shingles of the strip; and nails securing said strips together and the covering to the roof boards and disposed in slots of the several 25 strips transversely of each strip in a single series, the strips being so laid that the lowermost strips are disposed adjacently below the nails, respectively, and the uppermost strips cover the heads of said nails, whereby 30 any single shingle is pierced by only a single nail.
13. A roof covering consisting of four shingle strips laid to overlap, each such strip
- formed in its body portion with a plurality of sets of vertically alined slots, each such set consisting of comparatively large upper and lower slots and an intermediate small slot; and nails securing said strips together and the covering to the roof boards and disposed in the lower ends of the intermediate 35 slots, the strips being so laid that the top edges of the lowermost strips are disposed adjacently below the nails, respectively, and the uppermost strips cover the heads of said nails, whereby any one nail pierces only a 40 single strip.
14. A shingle strip consisting of a water-proof felt formed with a plurality of sets of slots consisting each of a plurality of vertically alined spaced slots of which the 45 upper and lower are duplicates so that the strips may be laid either way.
15. A shingle strip consisting of a water-proof felt formed with a plurality of sets of slots consisting each of a plurality of vertically alined spaced slots of which the upper and lower are duplicates so that the strip 50 may be laid either way, the respective outer ends of which upper and lower slots are removed somewhat from the top and bottom 55 edges of the strip to form continuous marginal portions along said edges.

Signed by me, this 26th day of December, 1917.

EDWIN A. MASTICK, JR.
